WALL SHELF

Fred D. Schuler, Cleveland, Ohio

Application August 2, 1952, Serial No. 20,880

Term of patent 14 years

(Cl. D33—3)

To all whom it may concern:

Be it known that I, Fred D. Schuler, a citizen of the United States, residing at Cleveland, in the county of Cuyahoga and State of Ohio, have invented a new, original, and ornamental Design for Wall Shelf, of which the following is a specification, reference being had to the accompanying drawing, forming part thereof and wherein:

Fig. 1 is a perspective front view of a wall shelf, showing my new design;

Fig. 2 is a top plan view of the design illustrated in Fig. 1;

Fig. 3 is a front elevational view of the design illustrated in Fig. 1;

Fig. 4 is an end elevational view thereof, taken from the right of Fig. 3; and

Fig. 5 is an end elevational view thereof, taken from the left of Fig. 3.

I claim:

The ornamental design for a wall shelf, as shown.

FRED D. SCHULER.
